United States Patent Office

Des. 207,044

Patented Feb. 21, 1967

207,044

BASE FOR A WATER FAUCET OR SIMILAR ARTICLE

Julius Hurwitz, 96-10 57th Ave.,
Forest Hills, N.Y. 11375

Filed Sept. 27, 1965, Ser. No. 87,178

Term of patent 3½ years

(Cl. D91—3)

FIGURE 1 is a top plan view of a base for a water faucet or similar article, showing my new design;

FIGURE 2 is a front elevational view thereof;

FIGURE 3 is a bottom plan view thereof; and

FIGURE 4 is an end elevational view thereof.

I claim:

The ornamental design for a base for a water faucet or similar article, as shown.
